UNITED STATES PATENT OFFICE.

CHARLES E. DE LONG, OF DALLAS, TEXAS, ASSIGNOR TO DE LONG ESCAPEMENT CO., INC., A CORPORATION OF NEW YORK.

ESCAPEMENT FOR WATCHES.

1,192,812.

Specification of Letters Patent. Patented July 25, 1916.

Application filed May 20, 1915. Serial No. 29,271.

To all whom it may concern:

Be it known that I, CHARLES E. DE LONG, a citizen of the United States, residing at Dallas, in the county of Dallas and State of 5 Texas, have invented certain new and useful Improvements in Escapements for Watches, of which the following is a specification.

My invention has relation to an escapement for watches or similar portable time 10 pieces and in such connection it relates more particularly to a means whereby the lever or fork carrying the fixed jewels or pallets may be adjusted with relation to its pivotal support to take up or compensate for inaccuracies in the shape or location of the lever.

Heretofore, in watches of even the finer grade, the escapement levers designed to carry fixed pallets or jewels vary in a more or less degree from the mathematically fixed 20 form, shape and location and it has heretofore been the usual custom in assembling the parts of the escapement to compensate for the inaccuracies, especially of location, by bending, twisting or otherwise manipulating 25 the fork or lever or by adjustment of the pallets to compensate for such inaccuracies which might exist. In cheaper grades of watches where the forks or levers and the other parts were more or less roughly made 30 the inaccuracies in the shape, and location were actually of less importance to correct since the accuracy of the time piece was not the first consideration in the sale of the watch. In finer grades however these inaccuracies are grave defects since they interfere with the proper operation of the movement in the keeping of accurate time.

In an application for patent filed by me under date of April 1st, 1915, Serial No. 40 18,470, I have shown and described a new form of escapement for watches wherein the fixed pallets project at right angles to the face of the fork or lever, said pallets having lifting angles coöperating with the lifting 45 angles of a club tooth escape wheel. My present invention is particularly adapted for use with the type of pallet and fork illustrated in said former application although it may if desired be used in escapements 50 where the fork or lever is provided with adjustable pallets or jewels.

In carrying out my present invention the connection between the fork or lever and its arbor is eccentrically devised and hence the 55 location of the lever in the escapement may

be adjusted by varying the degree of eccentricity existing between said arbor and the fork. In cheaper grades of movements it is sufficient for the purposes of this invention to provide a single eccentric adjustment between the arbor and the lever in which case the arbor itself may be eccentrically pivoted or supported, or the pivots for the arbor may be located centrally with respect to the arbor and said arbor may be supported in an eccentric collar interposed between lever and arbor. In finer grades of movements the eccentric relationship between arbor and lever may be of two fold character, the arbor being itself eccentrically pivoted or supported 60 in its bearings and supported in an eccentric collar interposed between the eccentric arbor and the lever. In this form of double eccentricity it is obvious that all parts may be turned to concentric position or zero or the 65 variations may be increased in a plus direction or decreased in a minus direction by the proper manipulation of both eccentric elements of the support for the lever.

The nature and scope of my invention will 70 be more fully understood from the following description taken in connection with the accompanying drawings forming part hereof, in which,

Figure 1, is a plan view of an escapement 75 forming the main features of my invention. Fig. 2, is a cross-sectional view enlarged of the fork or lever illustrated in Fig. 1, and Figs. 3, and 4, are views corresponding to Fig. 2 but illustrating modified forms of 80 the eccentric connection between the lever and the arbor.

Referring to the drawings, 1 is the fork or lever and 2 the escape wheel both of the usual standardized form, the teeth of the 85 escape wheel having a surface or lifting angle coöperating with the surface of lifting angle of the fixed pallets or jewels 3, carried by said lever 1 and in the preferred type of escapement illustrated these fixed pallets 90 3 project at right angles to the face of said lever 1.

The fork or lever 1 is carried by an arbor 4 which in the form shown in Figs. 1 to 3 is eccentric with relation to the pivots 5 105 which turn in bearings not shown. In the form of lever escapement shown in Figs. 1 and 2 the eccentric arbor 4 is driven through to frictionally engage an eccentric collar 6 and said collar 6 is driven through and pref. 110

erably upset to frictionally engage and inclose the lever 1. In this form one inclosing rim or flange of collar 6 is milled or knurled as at 7 along its perimeter and in all forms 5 of eccentric arbor 4 a portion of the arbor is cut away or flattened as at 8. The object of milling the edge 7 of collars 6 and of flattening the arbor as at 8 is to permit of the use of a tool in grasping and turning respectively collar 6 or arbor 4.

In the form shown in Fig. 3, the eccentric arbor 4 is driven through to frictionally engage the lever.

In the form shown in Fig. 4, the arbor 4^a 15 is of usual form having its pivots 5^a centrally disposed and this arbor 4^a is driven through to frictionally engage the eccentric collar 6^a which frictionally engages and incloses the lever 1. In the form shown in 20 Figs. 1 and 2, a double eccentric adjustment is possible. Thus the eccentric arbor 4 may be turned in either direction in the collar 6 and the collar 6 may be turned in either direction in the lever 1. The range of compensation to right or left is thus from double 25 the eccentricity or the added eccentricity of both collar and arbor to zero eccentricity in which the eccentricity of the collar offsets the eccentricity of arbor 4 to make the two 30 concentric.

In Fig. 3 the adjustment to right or left of the lever depends upon the movement of the eccentric arbor 4, but in Fig. 4 the adjustment is obtained by turning the eccentric collar 6^a the arbor 4^a turning therewith or 35 therein as desired.

Having thus described the nature and objects of my invention what I claim as new and desire to secure by Letters Patent, is,—

1. In a watch escapement, a lever, an arbor 40 and means for eccentrically connecting said lever with said arbor.

2. In a watch escapement, a lever, and an eccentric arbor carrying said lever.

3. In a watch escapement, a lever, an eccentric arbor and a means for eccentrically connecting said lever with said eccentric arbor.

4. In a watch escapement, a lever, an eccentric collar frictionally engaging said lever 45 and an arbor driven through and frictionally engaging said collar.

5. In a watch escapement, a lever, an eccentric collar frictionally engaging said lever, and an eccentric arbor driven through 50 and frictionally engaging said collar.

In testimony whereof I have signed my name to this specification.

CHARLES E. DE LONG.
